CAN OPENER

Gayne Chun, Madison, Wis.

Application May 22, 1953, Serial No. 356,681

3 Claims. (Cl. 30—14)

This invention relates to can openers and more particularly to a lever type can opener adapted to be held in the hand while being used to open a can.

It is among the objects of the invention to provide an improved can opener which includes a guide block adapted to engage and to be guided around the rim of a can and a hand lever pivotally mounted on the guide block and a blade connected to the hand lever and adapted to penetrate a can top and sever the top as the guide block is moved around the can rim; which has a projection on the end of the blade which engages the under side of the can top and prevents movement of the blade out of cutting engagement with the top during the severing operation; which firmly grips the can rim while the blade is being forced through the can top, so that the cutting action on the can top is accomplished entirely by a downward movement of the hand lever and advance of the opener is accomplished by a forward movement of the hand lever and additional force does not have to be exerted on the hand lever to hold the can opener in cutting engagement with the can; and which is simple and durable in construction, economical to manufacture, easy to use, and positive and effective in operation.

Other objects and advantages will become apparent from a consideration of the following description and the appended claims in conjunction with the accompanying drawing wherein:

Figure 1 is a top plan view of a can opener illustrative of the invention;

Figure 2 is a side elevational view of the can opener illustrated in Figure 1; and

Figure 3 is a cross sectional view on the line 3—3 of Figure 2.

With continued reference to the drawing, the can opener comprises a guide block, generally indicated at 10, of flat shape having substantially parallel face surfaces, a substantially straight bottom edge 11, a front edge 12 substantially perpendicular to the bottom edge 11, and a curved top edge 13 extending from the upper end of the front edge 12 to the rear end of the bottom edge 11. This guide block has an aperture 14 extending therethrough near the front edge 12 thereof with the center line of the aperture substantially perpendicular to a plane including the longitudinal center line of the bottom edge 11 and an annular boss 15 extends from one side of the guide block in surrounding relationship to the aperture 14.

A straight flange 16 projects from the same side of the guide block 10 from which the boss 15 projects, and this flange has its surface adjacent the boss 15 serrated and spaced from the adjacent surface of the boss a distance substantially equal to the thickness of the rim 17 of a can which the opener is adapted to open.

A lug 18 of rectangular shape projects from the side of the guide block 10 from which the boss 15 projects at the rear end of the bottom edge 11 of the block and is recessed to provide at its outer end a depending lip 19. The lip 19 is adapted to engage the inner side of the can rim 17, so that the lug 18 will ride on the upper edge of the can rim and will assist in guiding the guide block 10 around the top rim 17 of a can being opened by the can opener.

A pin 20 of cylindrical shape extends through the aperture 14 in the guide block and through the boss 15 and a hand lever 21 of flattened shape has near one end an aperture which receives the end of the pin 20 at the side of the block 10 remote from the boss 15. The hand

2

lever is rigidly secured to the pin 20 and projects radially therefrom beyond the rear end of the guide block to an extent sufficient to provide adequate leverage for the can opening operation.

5 A comma-shaped blade 23 has a substantially circular portion 24 provided with an aperture 25 which receives the end of the pin 20 at the outer end of the boss 15 and has a tail portion 26 projecting from the circular or annular portion 24. The tail portion has a convex edge 27 and a concave edge 28 which converge to a point at the outer end of the tail portion of the blade and this pointed end of the blade extends below the bottom edge of the guide block 10. The concave edge 28 is beveled to provide a cutting edge for the blade and a pointed projection 29 extends laterally from the side of the blade remote from the guide block 10 at the pointed end of the tail portion 26 of the blade.

The blade is rigidly secured to the pin 20 for movement with the hand lever 21 and the boss 15 has a thickness substantially equal to the width of the can rim 17, as illustrated in Figure 3.

20 The bottom edge 11 of the block 10 is recessed, as indicated at 30, between the flange 11 and the lug 18 to facilitate mounting the can opener in operative position on a can to be opened, and when the blade is fully retracted, the pointed end thereof is substantially flush with the edge of the recessed portion 30 of the bottom edge of the guide block and adjacent the inner side of the lug 18, as illustrated in broken lines in Figure 2.

25 In applying the can opener to a can to be opened, with the hand lever 21 in raised position, as illustrated in broken lines in Figure 2, the flange 11 is engaged under the rim at the top end of the can and the lug 18 is placed on the rim with the lip 19 in engagement with the inner surface of the rim. The hand lever 21 is then forced downwardly causing the pointed end portion of the blade 24 to penetrate the top of the can at the inner side of the can rim, as illustrated in Figure 3. In order to sever the can top from the tip rim, the downward movement of the handle is continued until the pointed end of the blade is lowered to an extent at which the projection 19 engages the top of the can top. When this occurs, the hand lever is again raised, the can opener is advanced along the rim of the can until the pointed end of the blade is adjacent the forward end of the cut previously made in the can top, and the handle is then forced downwardly to the extent indicated above. This operation is repeated until the can top has been substantially severed from the can rim and when this occurs, the opener is removed from the can by moving the hand lever outwardly and upwardly, lifting the lug 18 from the can rim and disengaging the flange 11 from the bottom surface of the rim. As the pointed end of the blade is removed, the projection 29 will engage the under surface of the can top and lift the top out of the open can.

30 In operation, the blade forces the severed portion of the top remaining attached to the can rim downwardly around the inner edge of the rim, so that there is no sharp edge on the open can which could injure the hands of a person handling the can.

35 The invention may be embodied in other specific forms without departing for the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

40 What is claimed is:

45 1. A can opener comprising a guide block having a substantially straight bottom edge and an aperture extending therethrough near one end thereof with the center line of the aperture substantially perpendicular to a plane including the center line of the bottom edge of said guide block, an annular boss projecting from one side of said guide block in surrounding relationship to said aperture, a straight flange projecting from said one side of the guide block along said bottom edge in spaced relationship to said boss and having a serrated surface adjacent said boss for engaging the bottom edge of a can rim sur-

rounding a can top, a lug projecting from said one side of said guide block at said bottom edge and at the end of said block remote from said aperture for guiding the corresponding end of the guide block on a can rim, a pin extending through said boss and said aperture, a hand lever secured at one end to said pin at the side of said guide block remote from said boss, and a blade secured to said pin at the outer end of said boss and having a pointed end portion projecting below the bottom edge of said guide block and a cutting edge extending from said pointed end to the portion of said blade surrounding said pin.

2. A can opener comprising a flat guide block having substantially parallel face surfaces, a substantially straight bottom edge and an aperture near one end thereof, a straight flange extending to one side of said guide block along said bottom edge and having a roughened upper surface, a lug extending to said one side of said guide block at a location along said bottom edge spaced from said flange and having at its outer end a depending lip adapted to engage the inner surface of a can rim, a pin journaled in the aperture in said guide block, a comma-shaped block having an annular portion surrounding and secured to said pin at said one side of the guide block and a pointed tail portion projecting from said annular portion and provided with a cutting edge, and a hand lever

25

secured at one end to said pin at the other side of said guide block with its longitudinal center line substantially perpendicular to the rotational axis of said pin.

3. A can opener comprising a flat guide block having substantially parallel face surfaces, a substantially straight bottom edge and an aperture near one end thereof, a straight flange extending to one side of said guide block along said bottom edge and having a roughened upper surface, a lug extending to said one side of said guide block at a location along said bottom edge spaced from said flange and having at its outer end a depending lip adapted to engage the inner surface of a can rim, a pin journaled in the aperture in said guide block, a comma-shaped block having an annular portion surrounding and secured to said pin at said one side of the guide block and a pointed tail portion projecting from said annular portion and provided with a cutting edge, and a hand lever secured at one end to said pin at the other side of said guide block with its longitudinal center line substantially perpendicular to the rotational axis of said pin, said block having its side adjacent said guide block spaced from the latter a distance sufficient to permit a can rim to pass between said blade and said guide block.
